UNITED STATES PATENT OFFICE

HERMAN T. KRAFT, OF AKRON, OHIO, ASSIGNOR TO THE GENERAL TIRE & RUBBER COMPANY, OF AKRON, OHIO, A CORPORATION OF OHIO

WATCHCASE HEATER

Application filed November 2, 1927. Serial No. 230,491.

This invention relates to heaters of the general type employed for vulcanizing rubber vehicle tires and more particularly for vulcanizing the outer casing and the inner tubes of pneumatic tires.

The invention has for an object to provide a vulcanizing heater composed of separable mold sections, one of which is carried by the piston of a fluid pressure cylinder and the other of which is carried by the open end of the cylinder and adapted to receive the pressure of the first mentioned section and to register therewith.

A further object of the invention is to provide a watch case vulcanizing heater with relatively axially movable mold sections for obtaining more complete registration of the mold sections.

An additional object is to provide a watch case heater with relatively movable mold sections; each of which is provided with a steam jacket and independent means connecting the steam jacket to a steam supply line.

A further object is to provide a watch case heater having mold sections hinged together so that one of the sections may be swung to an open position for insertion or removal of tires, the hinged section having a steam jacket and means for supplying steam to the steam jacket from a steam line positioned at the pivotal axis of the section.

A further object is to provide a vulcanizing heater having a pressure cylinder for applying pressure to the molds and a connection from the cylinder to the article in the mold to supply inflating pressure to the article being molded.

A further object is to provide a vulcanizing heater which has steam jacketed mold sections so constructed as to provide for more rapid and uniform transfer of heat to the article within the mold.

With the above and other objects in view, a preferred embodiment of the invention is shown, for illustrative purposes, in the watch case heater illustrated in the accompanying drawings hereinafter described and particularly set forth in the appended claims, to be considered with such variations and modifications thereof as will be apparent to one skilled

in the art to which the invention appertains.

Reference should be had to the accompanying drawings forming a part of the specification in which Figure 1 is a plan view of a watch case heater embodying the invention. 55

Fig. 2 is an end elevation of the heater.

Fig. 3 is a sectional side elevation of the heater with one end portion broken away and shown in central vertical section.

Referring to the accompanying drawings, 60 the heater chosen as illustrative of the present invention is mounted upon a suitable supporting stand 1, the body of the heater comprising a cylindrical casing 2, which is divided midway between its ends by a central vertical web 3.

The web 3 has a central boss 4 connected by radial reinforcing webs 4a with the outer wall of the casing. The central boss 4 forms a rigid support for op- 65

positely extending shafts 5, which are disposed axially of the casing. Each half of the casing on opposite sides of the central web 3 forms a cylinder and in each of these cylinders, there is mounted a piston 6, which has suitable peripheral packing 7 to provide a 70

substantially fluid tight fit between the piston and the wall of the cylinder. Each piston preferably has a heat insulating plate 42 on its pressure face and also has a central aper- 75

ture provided with a suitable bushing for receiving the axial shaft 5 and suitable packing 8 held in place by a collar 9 to provide a fluid tight joint between the piston and the shaft. The cylinders on opposite sides of the central web 3 are provided with air inlet ports to 80

which are connected fluid supply pipes 10

provided with suitable controlling valves 11, by means of which air may be supplied to or exhausted from the cylinders. The control 85

valves 11 are each connected to a vacuum line 90

10a and a fluid pressure line 10b.

Piston 6 is provided with a peripheral out- 95

wardly extending flange 12 and with an an- 100

ular flange 12a spaced inwardly from the outer flange. An annular shell 13 forming

the inner half of the tire mold is secured upon the outwardly projecting flanges 12 and 12a,

bridging the space between the flanges and

forming an annular steam jacket 14 along

the inner face of the shell 13. The shell 13

which is formed of a metal having relatively high heat conductivity is provided with regularly spaced inwardly projecting ribs 15, which serve to increase the surface area exposed to the steam within the steam jacket 14 and to provide a rapid and uniform transfer of heat from the steam jacket to a tire casing 25 within the mold. The tire casing is pressed outwardly against the walls of the mold by the inflated air bag 26.

The casing 2 has a heater door 16 hinged to each end thereof by means of a vertically disposed hinge 17. The heater door 16 also has an annular flange 16a that is adapted to seat against a correspondingly formed portion 2a of the casing when the heater door is closed.

Each heater door also has a mold section 18 secured thereto along its outer and inner marginal edges. The outer face of the mold section is spaced from the inner face of the heater door to provide a suitable steam jacket 19 for heating the mold. The outer face of the mold section has a series of heat conducting ribs 20 that are similar to the ribs 15 above described. The mold sections 13 and 18 have cooperating annular flanges 13a and 18a that register to complete the outer portion of the molding cavity. The inner portion of the molding cavity is completed by any conventional bead ring 20 or by cooperation of the inner edge portions of the mold sections as will be obvious to those skilled in the art.

Each heater door 16 has a central outwardly projecting hollow boss 21 arranged to receive the corresponding outer end of the shaft 5. Each of the hollow bosses 21 has a sliding nut 22 loosely mounted therein which is adapted to screw onto the correspondingly threaded end of the shaft 5. Each nut has a hand wheel 23 by means of which it can be easily and quickly screwed onto or off of the threaded shaft. The threaded nut is permitted considerable longitudinal movement in order that the heater door may be swung to its closed position before the nut 22 is threaded onto the shaft 5. A suitable handle 24 is mounted on the heater door opposite the hinge to facilitate the opening and closing of the heater door.

Each of the inner piston-carried mold sections 13 is provided with means for admitting steam into its steam jacket 14, which consists of short pipes 27 that are threaded into the flanges 12 to communicate with the steam cavity. The casing 2 has suitable slots 2b through which the pipes 27 extend to permit relative movement of the pistons in the casing. The short pipes 27 have suitable swivel joints 28 extending at right angles to the pipes 27 by means of which the pipes 27 are suitably connected to the main steam pressure line through connections that permit reciprocating movement of the pistons.

The outer mold sections are connected by steam pipes 30 and 31 which extend from the steam jackets 19 to adjacent the hinges 17 where they are connected by swivel joints 32 and 33 to steam pipes 34 and 35, which are coaxial with the axes of the hinges. The steam jackets 14 and 19 are provided with suitable drain cocks 36 and 37 by which water of condensation may be drained therefrom.

Each of the pistons 6 that carry the inner mold section has attached thereto a valve fitting 38 which communicates with the pressure chamber between the web and the piston and which has attached thereto a flexible hose 39 provided at its free end with a suitable coupling 40 by which it may be attached to an air bag within a tire casing in the mold, so that after a mold is closed and air pressure is admitted to the pressure applying cylinder, this pressure may be communicated to the air bag by manipulation of the valve control mechanism 41 that is carried by the heater door and so arranged as to engage the valve stem when the heater door is closed.

It will be obvious that the article to be vulcanized in the mold can be inflated from any suitable external fluid connection. Such an external inflating connection would be desired if the mold was operated by hydraulic pressure or if a different pressure or character of fluid were desired to operate the piston as compared with the inflating medium.

In the operation of the heater, a tire casing with an air bag therein is placed against the inner shell 13 and the hose 39 is coupled to the stem of the air bag. The heater door is then swung to a closed position and the nut 22 is screwed onto the shaft 5 to securely lock the mold door to the cylinder with annular flanges 2a and 16a in registered relation. Air is then admitted to the fluid pressure chamber whereby the mold is forcibly closed because of the very large area of the piston acted upon by the fluid pressure. After the mold is closed, the valve 38 is opened to inflate the air bag by manipulation of the valve control mechanism 41. The mold is heated by steam that is admitted through steam pipe 27 to the inner steam jacket 14 and through the steam pipe 30 or 31 to the outer steam jacket 19. The mold is preferably kept heated at all times during operation of the heater. When the vulcanization has been completed, air will be exhausted from the air bag and from the pressure cylinder. The pressure cylinder is then subjected to a vacuum by connection with the vacuum line 10a which draws the mold sections away from each other and causes the tire casing to be broken loose from the molding surface of the mold sections. The nut 22 is then unscrewed and the heater door opened to permit removal of the cured tire casing.

What I claim is :

1. A heater comprising a fluid pressure cylinder having a closed inner end, a piston in the cylinder, means for admitting fluid under pressure between the piston and closed end of the cylinder, a centrally disposed shaft rigidly secured to the closed end of the cylinder and extending through said piston, an inner mold section on the outer face of said piston, a complemental outer mold section, and means for detachably clamping said outer mold section to said shaft.

2. A heater comprising a fluid pressure cylinder having a closed inner end, a piston in the cylinder, means for admitting fluid under pressure between the piston and closed end of the cylinder, an annular inner tire mold section on the outer face of the piston, a complemental outer annular mold section, means for clamping said outer mold section against the open end of said cylinder, and means for admitting fluid under pressure from said cylinder through the piston to the interior of a tire casing within the mold.

25 3. A heater comprising a fluid pressure cylinder having a closed inner end, a piston in the cylinder, means for admitting fluid under pressure between the piston and closed end of the cylinder, an inner mold section on the outer face of said piston, a closure member hinged to the outer end of the cylinder, a complemental outer mold section carried by said closure member, means for securing said closure member to said cylinder to hold 30 the same in closed position, and means for delivering fluid under pressure from the interior of the cylinder to the interior of a tire within the mold comprising a valve controlled outlet carried by the piston and a flexible hose attached to the outlet and having means for attachment to an air bag within the mold cavity.

4. A watch case heater comprising a fluid pressure cylinder having a closed inner end, 45 a piston in said cylinder which has a covering of heat insulating material, means for admitting fluid under pressure between the piston and the closed end of the cylinder, an inner steam jacketed annular tire mold section on the outer face of said piston, a complemental outer steam jacketed annular mold section, means for clamping said outer section against the open end of the cylinder, and means for delivering steam to the jackets 50 of said mold sections.

5. A watch case heater comprising a fluid pressure cylinder having a closed inner end, a piston in said cylinder, means for admitting fluid under pressure between the piston and 60 the closed end of the cylinder, an inner steam jacketed annular tire mold section on the outer face of said piston, a complemental outer steam jacketed annular mold section, said outer mold section being hinged to said cylinder, a shaft fixed to the inner end of the

cylinder and extending through the piston, said shaft being threaded at its outer end, and a nut carried by said outer mold section for engagement with said threaded shaft.

6. A heater comprising a pair of relatively 70 movable supporting members, each having an annular recess, a pair of complemental tire mold sections formed to provide an annular mold cavity between them, each of said mold sections being secured to a supporting member and closing the annular recess thereof to form a steam chamber, each mold section being composed of a metal of high heat conductivity and having integral ribs on their outer faces projecting into the steam chamber.

In testimony whereof I affix my signature.
